CHARLES R. MESTON AND ALECK W. MESTON, OF YONKERS, NEW YORK, ASSIGNORS TO THE STACOLD CORPORATION, OF NEW YORK, N. Y., A CORPORATION OF NEW YORK.

PUMP.

Application filed March 11, 1926. Serial No. 93,820.

This invention relates to pumps and particularly to air or gas pumps such as are used in refrigerating apparatus.

The invention has been particularly worked out in connection with pumps utilizing intermeshing gears for pumping air or gas. With this type of pump, it is essential that the gear teeth fully intermesh and that there be no leakage of air around the teeth in the casing at the outlet side of the pump or leakage from the casing around the pump shaft. When the pump is used as a high pressure pump, it is very difficult to prevent leakage of air or gas from the discharge side of the pump. Furthermore, the high pressure acting on the pump elements tends to exert a thrust thereon and cause wear of the gears and contacting parts of the pump.

20 The invention has for its salient object to provide a pump so made as to obtain extreme accuracy in construction at a minimum manufacturing cost.

Another object of the invention is to provide a pump of the character described so constructed that there will be practically no leakage at the outlet or high pressure side of the pump.

Another object of the invention is to provide a structure of the character described in which the pressure is equalized at the ends of the gear elements so that no appreciable thrust is exerted on the gears.

Another object of the invention is to provide a pump of the character described in which the drive shaft is so connected to the pump that no leakage from the casing will occur around the shaft.

Further objects of the invention will appear from the following specification taken in connection with the drawings, which form a part of this application, and in which

Fig. 1 is a sectional elevation of a pump constructed in accordance with the invention;

Figs. 2 and 3 are transverse sectional elevations taken substantially on lines 2—2 and 3—3 of Fig. 1;

Fig. 4 is a sectional elevation taken substantially on line 4—4 of Fig. 1;

Fig. 5 is a sectional elevation taken

through the gears and illustrating one manner of mounting the gear elements in the casing;

Fig. 6 is a view similar to Fig. 5 but taken through one of the discharge openings; and

Fig. 7 is a sectional elevation, broken away, showing other driving connections and sealing means.

The invention briefly described consists of a pump comprising a casing bored to receive the gear elements and bearing plugs and bushings for the gear elements. By mounting the gears and shaft bearings in straight bores, the bearings, bushings and gears will be positioned in accurate alignment thus providing extreme accuracy at a minimum of expense in manufacturing.

If desired, to provide for taking up wear or other contingencies and to further insure an accurate fit, the plugs or bearing boxes have their centers disposed very slightly eccentric to the center of the bores in the casing in such a manner that the pump gearing will accurately fit the casing at the discharge side of the pump but will clear the casing at the inlet side of the pump. This prevents leakage at the high pressure side of the pump and prevents the gears from dragging or rubbing on the casing at the intake side of the pump in case the gear shafts become worn or the bearings permit the gears to get out of alignment.

Means is also provided in the pump for eliminating end thrust and also for preventing leakage of the air or gas from the pump casing around the drive shaft and for preventing air from leaking into the casing. This is accomplished in one form of the invention by providing a drive shaft with a longitudinal recess at one end for receiving the gear shaft. The recessed end of the drive shaft is flanged and the flange engages a spring pressed collar, the spring being enclosed within an expandable and contractible metallic casing. The spring presses the flange into engagement with the collar and also presses the collar against a wall of the casing. The drive shaft is splined or keyed to the gear shaft. In another embodiment the drive shaft is splined or otherwise connected to drive one of the

gears and is extended out through the casting end. A flange on the shaft engages a collar as in the first form described and prevents leakage. By means of this construction the gear shaft floats in its bearing and end thrust is largely eliminated.

In the form of the invention illustrated, sealing liquid is conducted to the ends of the gears thus equalizing the pressure at the ends of each gear and a lubricant separate and distinct from the sealing liquid is used for lubricating the bearings.

Further details of the invention will appear from the following description.

15 The pump casing consists of a body portion 10 and end plates 11 and 12. The body portion is preferably cast in a solid block and is bored longitudinally to form straight bores 15 and 16. (See Fig. 3.) The bores 20 15 and 16 as illustrated, consist of overlapping cylindrical openings which intersect in a common plane 17.

There is positioned at each end of each bore a bearing box or plug 20 and in these 25 bearing boxes or bearing plugs are mounted ball bearings 21. The bearing boxes or plugs 20 have substantially cylindrical outer surfaces but are formed with flat sides 22 adapted to be positioned in alignment with the 30 common plane 17.

The pumping elements consist of a pair of intermeshing gears 25 and 26, herringbone gears being illustrated. The gear 25 is mounted on a shaft 27 and the gear 26 35 is mounted on a shaft 28, the shafts 27 and 28 being mounted in the bearings 21 carried by the plugs 20.

The straight bores thus receive the gears, shafts and shaft bearings and because of 40 this construction the elements specified can be accurately aligned.

As shown in Figs. 5 and 6, the bores 15 and 16 intersect in a knife edge 30 at the high pressure or discharge side of the pump 45 and it is very essential that the gear teeth 31 and 32 of the gears 25 and 26 accurately fit the casing at this knife edge so as to prevent escape of the high pressure air or gas. This is accomplished by locating the plugs 50 or bearing boxes 20, the gears, and gear 55 shafts in the straight bores 15 and 16.

It has been found advantageous to compensate for wear and to further insure an accurate fit of the pump elements in the 55 bores by locating the centers of the plugs or bearing boxes 20 slightly eccentric to the centers of the bores 15 and 16. Such a structure is shown in Figs. 5 and 6, wherein in the centers of the plugs are located at 60 x and the centers of the bores are located at y . The point x is located on a line disposed substantially 45° from the line $y-y$ connecting the centers of the bores. By so 65 positioning the centers of the bearing boxes or plugs, it will be clear that the gear teeth

31 and 32 will be positioned in full intermeshing relation with reference to each other and these teeth will also accurately fit the casing at the knife edge 30. Furthermore, the gears will be so located that 70 a clearance z will be formed at the intake side of the pump, thus preventing the gears from dragging on the casing or rubbing thereagainst at this side of the pump. In practise, the centers x are displaced from 75 centers y only a few thousandths of an inch.

The air or gas or other substance to be pumped is admitted to the casing body 10 through a conduit 40 and opening 41 formed in the casing. The opening 41 communicates at its inner end with a recess 42 formed in the casing body opposite the knife edge 30.

The air or gas or other substance being pumped leaves the casing body through 80 openings 45 and 46 formed in the plugs 20 and communicating with discharge conduits 47 and 48.

In the form of the invention shown in Fig. 1, the drive shaft of the pump is shown 90 at 50 and is provided with a longitudinal recess 51. The shaft 50 has a flange 52 formed on the end of the recessed portion thereof, the flange being adapted to seat against a portion 53 of the casing end 95 plate 12.

The end plate 12 has formed thereon a boss 54 into which the shaft 50 extends and the open end of the boss is closed by a cap 55. A spring 56 seats at one end against the cap 55 and at its opposite end against a collar 57 which carries a packing 58 adapted to engage the flange 52. A flexible bellows is secured at one end to the collar 57 and at its other end to a washer 59 which is secured by the cap 55 against the outer end of the boss 54.

From the showing in Fig. 1 it will be seen that the spring 56 presses the collar 57 and packing 58 against the outer surface of the flange 52 and also presses the flange against the outer surface of the portion 53 of the end plate 12, thus tending to prevent the escape of any of the sealing liquid from the casing.

In Fig. 7 a similar shaft seal is illustrated but in this embodiment a flange 52^A is formed on the shaft 27^A and this shaft is extended through the end plate and cap 55. The gear 25 is splined to or mounted on 115 the squared portion 27^B of the shaft and is slidable thereon but rotatable therewith. The flange 52^A bears against collar or washer 57 as before and the spring 56, washer 59, and bellows between washer 69 and collar 57 120 operate as in Fig. 1.

The body 10 of the pump casing is mounted on a base plate 60 which in turn is mounted on and forms the top for a cooling reservoir or chamber 61. The casing body 10 has formed in its outer surface a pair 130

of annular recesses 62 and 63 which extend around the body 10 and are connected by a passage 64. The passage 64 at the top of the casing is covered by a plate 65. The 5 annular passages 62 and 63 communicate through openings 66 in the base 60 with the cooling chamber or reservoir 61. The cooling fluid enters the reservoir 61 through a conduit 67 and leaves the casing by a conduit 68 which is secured to plate 65 and extends therethrough.

In the embodiment of the invention illustrated, the liquid used for sealing the pump elements enters the cooling reservoir or 15 chamber 61 through a conduit 70 and passes around a coil 71 disposed in the chamber 61 and through a conduit 72 to a strainer 73.

From the strainer 73 the sealing liquid passes through an opening 74 in the strainer casing into a conduit 75 which leads to annular recesses or grooves 76 formed on the inner surface of the plugs 20 disposed at the ends of the gear 26. (See Fig. 1.) Also, 20 on referring to Fig. 2, it will be seen that the sealing liquid passes through a conduit 77 to a conduit 78 which is connected by conduits 79 and 80 to the grooves 76 formed in the plugs 20 disposed at the ends of the gear 25.

30 The conduit 77 also communicates with a conduit 81 which in turn conducts sealing liquid through minute passages 82 to the gear teeth, thus sealing the contact between the teeth and the casing at the high pressure side of the pump.

Conduit 79 also conducts sealing liquid to a conduit 83 which in turn conducts the liquid to the outwardly extending portion of the shaft 27 and the liquid thus conducted 40 will seal the contact between the collar 52 and portion 53 of the end plate 12.

The recess or chamber in the boss 54, around the bellows, is filled with oil at all times, due to the oil or sealing liquid that 45 is forced out between flange 52 and wall 53 and to insure a supply of lubricant or oil in the chamber when the pump is started an opening 84 is provided in the boss. A plug 85 tightly closes this opening when sealing liquid is not being supplied to the chamber.

When the pump shuts down, unless all the valves are tight, there may be a vacuum in the pump and this tends to draw air into the pump. The admission of air is very deleterious to the pump especially where sulphur dioxide is the refrigerant and so it is very important to prevent air from entering. This important function is performed by 55 the bellows and by sealing liquid in the chamber in boss 54, which seals the contact between washer 57 and flange 52 or 52A.

In the form of the invention illustrated in the drawings, the sealing liquid is not used 60 to lubricate the bearings but a separate and

distinct lubricant is used. It will be noted that the end plates 11 and 12 are provided with recesses or pockets 90 disposed in alignment with the bearings 21 and openings in the end plates through which lubricant can 70 be introduced therein are closed by plugs 91. Any desired form of lubricant or grease may be utilized for the bearings.

It will be understood that the sealing liquid passes from the pump with the air 75 or gas pumped, is extracted from the gas in a separator and returns to the coil 71 through pipe 70 and under pressure of the gas or air delivered by the pump.

From the foregoing specification is will 80 be seen that a pump structure has been provided in which the gear elements will accurately fit the casing and prevent escape of air or gas and loss of pressure at the discharge side of the pump and in which the 85 pumping elements will be free from or clear of the casing at the intake side thereof. Furthermore, by reason of the fact that the sealing fluid passes to both ends of the pump shafts, and by reason of the form of shaft 90 seal and elimination of stuffing boxes, the pressure is equalized and end thrust is minimized. The pump drive shaft has been so connected to the gearing that leakage from the casing around the shaft is eliminated 95 or practically eliminated and the pressure within the casing tends to prevent escape of air or gas from the casing.

Although certain specific embodiments of the invention have been particularly shown 100 and described, it will be understood that the invention is capable of modification and that changes in the construction and in the arrangement of the various cooperating parts may be made without departing from the 105 spirit or scope of the invention as expressed in the following claims.

What we claim is:

1. In combination, a casing, a shaft mounted in said casing and extending 110 through the wall thereof, a drive shaft telescoping with said shaft extension keyed thereto and slidably relative thereto, a flange formed on the outer telescoping member, a collar surrounding said member and engaging said flange, resilient means pressing said collar against said flange and an expandable and a contractible sheath surrounding said resilient means and secured to the collar and casing for preventing sealing liquid from 115 leaking thereon.

2. In combination, a casing, a shaft mounted therein and extending outwardly through one wall thereof, a shaft having a recessed end slidably receiving the extended 125 end of said first shaft and having a flange on the end thereof, a boss on said casing surrounding said shafts and flange and having an opening forming a pocket, a cap on the outer end of said boss, the shaft flange be- 130

ing disposed in engagement with the wall of the casing, a washer surrounding said shafts and engaging said flange and a spring mounted between said cap and said washer for pressing the washer against the flange and the flange against the casing wall and a flexible metallic sheath secured between said cap and said washer and surrounding

said spring for preventing sealing fluid from escaping.

In witness whereof, I have hereunto set my hand this 8th day of March, 1926.

CHARLES R. MESTON.

In witness whereof, I have hereunto set my hand this 8th day of March, 1926.

ALECK W. MESTON.
